UNITED STATES PATENT OFFICE.

WILLIAM HAESSE, OF MIAMI, FLORIDA.

SPOON AND FORK HOLDER.

Application filed April 7, 1927. Serial No. 181,794.

This invention relates to a holder, and more particularly to a design of holder by means of which a knife, fork or any other appropriate article may be supported in a predetermined position relative to another article, such as a dish, and has for its primary object to simplify the construction of such a device so that the same may be economically manufactured and capable of being very readily arranged in place and, when in place, effectively held against displacement.

An object of the invention is the construction of a holder of neat, sanitary appearance which can be very readily arranged in place. 15 A feature of the invention is the construction of the holder from a single length of wire bent into a novel shape to effectively embrace a dish and effectively engage the article supported.

20 With these and other objects in view, my invention will be better understood from a description of the invention taken in connection with the accompanying drawing, wherein:

25 Figure 1 is a perspective view of the holder in applied position;

Figure 2 is a cross sectional view;

Figure 3 is a front elevation.

Again referring to the drawing illustrating one of the many constructions of my invention, the numeral 1 designates the holder in its entirety consisting basically of a clip 2 and a clip 3, the latter effectively embracing the dish 4 and the former effectively engaging a spoon 5 or other similar article. This holder is formed from a single length of wire bent to provide the diverging, vertically extending limbs 6 which are attached together by the connector 7. This connector is 40 bent into zigzag formation to provide notches 8 to receive the handle of the spoon or any other object.

45 Arms 9 continuations of the limbs are also arranged in divergent formation and curved to effectively engage the inner surface of the dish, and to complete the invention I provide the yoke 10 connecting the arms together and curved to effectively engage the outer surface of the dish, and to increase its effective engagement I provide a lip 11.

55 From the foregoing description taken in connection with the accompanying drawing, it will be apparent that I provide a holder that may be economically manufactured and one that may be formed entirely of wire so bent and shaped as to effectively support ar-

ticles in their proper positions, while at the same time effectively engaging the receptacle or dish so as to prevent displacement or the accidental dislocation of the holder. It will also be appreciated that the article is very sanitary, due to its formation, which enables the same to be very readily cleaned. As the holder may be made of inexpensive material or plated in an inexpensive manner, it will be understood that the device may add to the ornamental effect of the dish, besides being capable of performing a very useful function.

It is, of course, to be understood that the device may be constructed in various other manners and given various other shapes than illustrated and, therefore, I do not desire to be limited in any manner except as set forth in the appended claims.

1. A holding device of the class described 75 comprising upwardly diverging supporting legs, a cross piece extending between the legs and provided with a bend to afford a seat for an article to be supported, arms extending upwardly from the lower ends of the legs, 80 and a bearing member extending between and connecting the arms at the outer ends thereof and having portions extending substantially opposite the said arms, whereby, to provide, in connection with said arms, a 85 frictional clamp for engagement with the margin of a dish or the like.

2. A holding device of the class described comprising an upright supporting portion having a seat therein to accommodate the 90 handle of a spoon or the like, and an attaching portion comprising arms curving upwardly and outwardly from the supporting portion, and a clamping portion extending between and connecting the arms and having 95 portions extending in spaced relation to the arms of the attaching portion to coact therewith to grip the rim of a dish or the like.

3. A supporting device of the class described comprising a supporting member including upwardly diverging legs, a portion connecting the upper ends of the legs and provided with a bend providing a seat for the handle of a spoon or the like, arms extending upwardly and outwardly from the lower ends 105 of said legs and formed to embrace the upper side of the rim of a dish or the like, and a clamping portion extending between and connecting the ends of the arms and including upwardly diverging end portions located 110 substantially opposite the arms to coact therewith to grip the rim of a dish or the like and

an intermediate bowed portion located opposite the space between the lower ends of the arms.

4. A supporting device of the class described comprising a supporting member including upwardly diverging legs, a portion connecting the upper ends of the legs and provided with a bend providing a seat for the handle of a spoon or the like, arms curved upwardly and outwardly beyond the plane occupied by the legs and at an acute angle to the legs, the arms being provided with

bends to embrace the upper side of the rim of a dish or the like, and a clamping portion extending between and connecting the ends 15 of the arms and including end portions located substantially opposite respective ones of the arms and an intermediate bowed portion located opposite the space between the lower ends of the arms, the said clamping portion 20 being curved to correspond substantially to the curvature of the arms.

In testimony whereof I affix my signature.

WILLIAM HAESE.
